DESIGN FOR A BELT BUCKLE

Harry Stelzer, Forest Hills, N. Y.

Application March 1, 1941, Serial No. 99,287

Term of patent 14 years

To all whom it may concern:

Be it known that I, Harry Stelzer, a citizen of the United States, residing at 77-35 113th Street, Forest Hills, in the county of Queens and State of New York, have invented a new, original, and ornamental Design for a Belt Buckle, of which the following is a specification, reference being had to the accompanying drawing, forming part thereof.

In the drawing:

Fig. 1 is a front elevational view of a belt buckle showing my new design.

Fig. 2 is a top plan view of the buckle.

Fig. 3 is a left side elevational view of the same.

Fig. 4 is a right side elevational view of the same.

I claim:

The ornamental design for a belt buckle, as shown.

HARRY STELZER.
